PULL TOY

John T. Generale, Pelham Manor, N. Y.

Application April 24, 1945, Serial No. 590,001

11 Claims. (Cl. 46—98)

This invention relates to toys and is particularly directed to a pull-toy for children.

An object of this invention is to provide a pull-toy comprising a dog-simulating member so constructed and arranged that when the toy is at rest, the "dog" assumes a sitting position with his tail down, and when the toy is pulled, the "dog" will stand up and the tail will simultaneously be raised.

Another object of this invention is to provide a pull-toy on wheels provided with means to produce a sound simulating a dogs' growl, at intervals while the toy is being pulled.

Another object of this invention is to provide an animal-simulating toy provided with members simulating the hind legs and tail, said members being connected for simultaneous movement, so that movement of the tail-simulating member accompanies movement of the hind leg-simulating member.

Still another object is to provide a toy of the character described having a pull string connected to the tail-simulating member so that a pull on the string will cause the tail-simulating member to stand up and will simultaneously move the hind legs from a horizontal to vertical position.

Yet another object of this invention is to provide a toy of the character described comprising an animal-simulating member having a body, front and hind legs on wheels, and provided with a tail, the arrangement being such that the "animal" appears normally to be in a sitting position with the hind legs projecting forwardly, and the body inclined, with the rear end of the body contacting the floor and the tail projecting rearwardly, said toy being provided with a pull string, and the arrangement being such that when the string is pulled, the tail is swung upwardly and the hind legs are pulled to vertical position so that the "animal" appears to be standing.

Still a further object of this invention is to provide a strong, compact and durable toy of the character described which shall be relatively inexpensive to manufacture, amusing to play with, and yet practical and efficient to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is 55

shown various possible illustrative embodiments of this invention:

Fig. 1 is a side elevational view of a toy embodying the invention.

5 Fig. 2 is a rear elevational view of the toy shown in Fig. 1.

Fig. 3 is a vertical section through the toy and showing the same in sitting position.

10 Fig. 4 is a cross-sectional view taken on line 4—4 of Fig. 1; and

Fig. 5 is a cross-sectional view taken on line 5—5 of Fig. 1.

Referring now in detail to the drawing, 10 designates a toy embodying the invention. The 15 same comprises a body 11, a front leg-simulating member 12 on wheels 13, and a hind leg-simulating member 15 on wheels 16.

The body 11 may be made from a flat piece of 20 wood, composition or any other suitable material, and it is shaped to represent the contour of the body and head of a dog or other animal. The head may be painted on the outside as shown at 18 to simulate a dog's face. Said body 11 is formed on its rear end with a slot 20, which extends to a downwardly and forwardly inclined line 21 shown in Fig. 3 of the drawing. Said body is furthermore formed with a drilled opening 22 communicating with the slot 20 and substantially in horizontal position and somewhat below the top of the body. The drilled opening 22 terminates short of the head. The body is formed with another drilled opening 23 extending downwardly from the top and communicating with the opening 22. The slot 20 in the body 25 forms a pair of parallel portions 25 carrying a transverse pivot pin 26 which traverses the slot 20. Disposed within slot 20 and pivoted to pin 26 is a lever 27, which is formed with an opening 28 to receive the pivot pin 26. At the upper end 30 of lever 27 is a portion 29 which may be painted or otherwise decorated to simulate a dog's tail.

The hind leg-simulating member 15 comprises a pair of "legs" 30 pivoted at their upper ends to the pivot pins 26 and located on the outside of 45 the body 11. The legs 30 are formed, adjacent their lower ends, with aligned through openings 31 carrying a transverse shaft 32. The shaft 32 also passes through an opening at the lower end of lever 27.

50 The wheels 16 are mounted on the outer ends of shaft 32.

It will now be understood that when the toy is in the sitting position shown in Fig. 3, the legs 30 project forwardly and the body rests on its rear end. The lever 27 is in horizontal position

with the tail 29 projecting rearwardly. However, should the outer end of lever 27 be lifted to swing the lever about the pivot pin 26, the legs 30 together with lever 27 will swing to the vertical position shown in Fig. 1 to bring the dog to standing position.

Attached to lever 27 above the pivot pin 26 is a pull string 34. The pull string may pass through an opening 35 in the lever and may be formed with a knot 36 at its outer end received in a suitable recess 37 gouged out of the lever. The pull string 34 passes through slot 20 and passages 22, 23. A hand grip or ball 39 may be provided at the front end of the pull string. Thus when the toy is at rest, the "dog" assumes a sitting position; when the "dog" is pulled, it will stand up and roll forwardly.

The front leg member 12 is formed with a slot 40 at its upper end to receive the body 11. On opposite sides of slot 40 are parallel portions 41 which may receive nails 42 or other fastening means driven into the body to fix member 12 to the body.

The member 12 is formed furthermore at its lower end with a slot 46 forming parallel side walls 47. Said member 12 is formed furthermore with a vertical drilled opening 48 communicating with the slots 40, 46. The parallel walls 47 are formed with aligned openings 50 rotatably receiving a transverse shaft 51 on which the front wheels 13 are mounted. Fixed to shaft 51 as at 60a and disposed within slot 46 is a segmental gear 52. The wheels 13 are fixed to the shaft 51 in any suitable manner so that the shaft and segmental gear 52 rotate with the wheels.

Attached to the underside of the body 11 as by nails or other fastening means 60, is an angle-shaped spring 61 which comprises a portion 62 located within slot 40 and formed with openings to receive the fastening means 60. Extending from said portion 62 is a portion 64 passing through opening 48. The lower end on spring portion 64 is adapted to engage the teeth of the segmental gear 52. At the bottom of groove 40 is a plate 70 formed with an opening 71 through which spring portion 64 passes. As the wheels 13 rotate when the toy is being pulled, the teeth of the segmental gear 52 will engage the outer end of spring portion 64 to produce a rattle simulating the growl of a dog.

It will be understood that when the toy is in the standing position shown in Fig. 1, the center of shaft 32 is sufficiently forward of the center of pivot pin 26, to preclude the possibility of the toy remaining in upright position when the pull is relaxed in string 34.

It will thus be seen that there is provided a device in which the several objects of this invention are achieved, and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, what I claim as new and desire to secure by Letters Patent is:

1. A toy comprising a body-simulating member, a leg simulating member pivoted to the body, a lever pivoted at an intermediate portion thereof to the body, means to attach one end of the lever to the leg-simulating member, the other end

of said lever being provided with a tail-simulating portion.

5 2. A toy comprising a body-simulating member, a leg-simulating member pivoted to the body, a lever pivoted at an intermediate portion thereof to the body, means to attach one end of the lever to the leg-simulating member, the other end of said lever being provided with a tail-simulating portion, and means to swing said lever about its pivot.

10 3. A toy comprising a body-simulating member, a leg-simulating member pivoted to the body, a lever pivoted at an intermediate portion thereof to the body, means to attach one end of the lever to the leg-simulating member, the other end of said lever being provided with a tail-simulating portion, and means to swing said lever about its pivot, said means comprising a pull string, said body being formed with a through passage, and said pull string extending through said passage.

15 4. A toy device simulating an animal, and comprising a body, a hind-leg-simulating member on said body, a tail-simulating member on said body, and means to connect said hind leg-simulating member to said tail-simulating member for simultaneous movement, and a pull string for pulling the toy, attached to one of said members.

20 5. A toy device simulating an animal, and comprising a body, a hind-leg simulating member on said body, a tail-simulating member on said body, means to connect said hind leg-simulating member to said tail-simulating member for simultaneous movement, a pull string for pulling the toy, attached to one of said members, a front leg-simulating member attached to said body, and wheels on said front leg- and hind leg-simulating members.

25 6. A toy comprising a body, the rear end of the body being formed with a slot, a pivot pin on said body traversing the slot, a lever passing through the slot and pivoted to said pivot pin, leg-simulating members pivoted to said pivot pin, a shaft passing through the lower end of said lever and leg-simulating members, wheels on said shaft, and said lever being formed at its upper end with a tail-simulating portion.

30 7. A toy comprising a body, the rear end of the body being formed with a slot, a pivot pin on said body traversing the slot, a lever passing through the slot and pivoted to said pivot pin, leg-simulating members pivoted to said pivot pin, a shaft passing through the lower end of said lever and leg-simulating members, wheels on said shaft, and said lever being formed at its upper end with a tail-simulating portion, said body being formed with a through passage, and a pull string attached to the lever above the pivot pin and passing through said passage.

35 8. A toy comprising a body, a front leg-simulating member fixed to the body, a rear leg-simulating member pivoted to the body, wheels on said leg-simulating members, and a pull string connected with said rear leg-simulating member at a point spaced from the pivotal connection between said rear leg-simulating member and body.

40 9. A toy comprising a body, a front leg-simulating portion fixed to the body, a hind leg-simulating member pivoted to the body, tail-simulating means fixed to the hind leg-simulating member and adapted to rotate therewith as a unit relative to the body, and means to cause rotation of said unit.

45 10. A toy comprising a body, a front leg-simulating

lating portion fixed to the body, a hind leg-simulating member pivoted to the body, tail-simulating means fixed to the hind leg-simulating member and adapted to rotate therewith as a unit relative to the body, means to cause rotation of said unit, and wheels on said front and hind leg-simulating members.

11. An animal-simulating toy adapted to assume both an upright position and a sitting position, and comprising a body, a front leg member fixed to the body, a rear leg member pivoted to

the body, wheels on said leg members, the axis of the rear wheels being at all times forward of a perpendicular dropped through the center of said rear leg pivot, and a pull string connected with said rear leg member at a point remote from its said pivot whereby when a pull is exerted on the string the toy will assume the erect position, and when the pull is relaxed and the string slack, the toy will assume the sitting position.

JOHN T. GENERALE.
